UNITED STATES PATENT OFFICE.

SAMUEL S. CHESNIN, OF NEW YORK, N. Y.

GARMENT.

Application filed July 26, 1926. Serial No. 125,021.

The present invention is concerned with the provision of that type of garment which is commonly formed with a self-adjusting elastic body-encircling portion, such as a 5 waistband, arm band, or leg band. While the invention finds its preferred embodiment in the waistband of a woman's undergarment, it is to be understood that it may have a wide range of utility in the art, and 10 is applicable equally well to a sleeve band or arm band.

The common practice of forming elastic waistbands in women's undergarments is to secure the ends of an elastic tape within 15 the tubular waistband of the garment. The natural tendency of the tape to contract gives the waistband a crumpled or shirred appearance and permits the waistband to rapidly expand for purposes of self adjustment.

When the garments are washed, there is no way of removing the elastic member without ripping open the tubular waistband and taking out the stitching which secures 25 the elastic tape. In consequence, the garments are washed with the tapes in place, the tapes rapidly rotting, breaking, and becoming altogether inefficient in use.

I propose to form a garment having a 30 tubular body encircling portion, such as a waistband, and to detachably mount an elastic tape in the tubular waistband in such a manner that the tape may be readily removed and replaced when it is desired to launder the garment. The tapes, when the 35 garments are in position are always under a considerable strain. That is to say, the tapes are under tension and are quite likely to pull away from any ordinary anchorage, 40 such for instance as a button and button-hole, or a snap fastener. As a further feature of the invention, therefore, I provide novel anchoring means for securely anchoring the ends of the tape, so that there is no 45 danger of the tape-attaching means being torn away while the garment is worn, with consequent embarrassment to the wearer.

Objects of the invention are to provide a 50 garment of the general character noted above, which will be of simple practical construction, neat and attractive in appearance, and capable of manufacture with comparative economy.

With the above noted and other objects in 55 view, the invention consists in certain novel features of construction and combinations

and arrangements of parts, as will be more fully hereinafter set forth and pointed out in the claims. The invention may be more fully understood from the following description in connection with the accompanying drawings, wherein—

Fig. 1 is a perspective view of a garment embodying the present invention.

Fig. 2 is an enlarged sectional view on the 65 line 2—2 of Fig. 1.

Fig. 3 is an enlarged view in inside elevation of the portion of the waistband to which the tape anchorage is secured.

In the drawings I have elected to show 70 the invention as embodied in the waistband of a woman's undergarment, such as a conventional step-in, indicated generally by the reference character 10. It is to be understood however, that the device may be applied with equal facility to arm bands or leg bands, and that the term "body-encircling element" as used in the specification and claims, is intended to cover not only waistbands, but all other contractile annular elements which grip the body of a wearer.

The waistband of the garment indicated at 11 is of tubular formation throughout its length. The major portion of the waistband being adapted to serve as a tunnel or 85 housing which receives a removable elastic tape 12. With the tape 12 in position, the major portion of the waistband is shirred as indicated, due to the contraction of the waistband by the tape. A small section 13 90 of the band, preferably at the rear, is not acted upon by the tape and at the ends of this section, I mount anchorages 14 for receiving the attaching devices 15 carried by the ends of the tape 12.

The tape ends project through openings 16 in the inner lamination of the tubular waistband 11. Buttons, snap fasteners and other types of conventional securing devices are altogether unsuitable for use as tape 100 anchorages, due to the fact that the tape is under considerable strain when the garment is worn, and would readily pull away from such fasteners. Fastener elements 15 therefore are preferably in the nature of metal hooks formed with tongue portions 17 securely engaged with the ends of the tape by a folding and pressing operation. The tape end is laid upon one of the plates 15, the tongues folded over upon it, and 105 forced down to firmly clamp the tape. The hooks preferably coat with eyelets 18, se-

cured in position in the waistband, these eyelets being in the nature of relatively heavy rivet-like members which are proof against dislocation or pulling out under the strain imposed thereon by the tape. Preferably the outer ply of the waistband is provided with patches 19 concealing the eyelets and the ends of the hooks which project therethrough, so that the garment in external appearance will be entirely conventional.

Various changes and alterations might be made in the general form and arrangement of parts described without departing from the invention. Hence I do not wish to limit myself to the details set forth, but shall con-

sider myself at liberty to make such changes and alterations as fairly fall within the spirit and scope of the appended claim.

I claim:

A garment including a body encircling band of tubular formation throughout the major portion of its length, an elastic tape removably mounted in the tubular portion of the band and having its ends projecting through openings in the inner side thereof, hooks carried by the ends of the tape and engageable with eyelets riveted into the band, and patches over the outer face of the eyelets to conceal the ends of the hooks.

SAMUEL S. CHESNIN.
